MANICURING AID

Lorena G. Lewis, New York, N. Y., assignor to
Parx Products Corp., New York, N. Y., a cor-
poration of Delaware

Application February 13, 1948, Serial No. 8,082

3 Claims. (CL. 132—73)

1

This invention relates to improvements in means for manicuring and otherwise beautifying the nails of the human digits.

It is at present and has been for some time past the fashion to apply polishing material to the human nails in the form of a liquid which is permitted to dry and which thereafter assumes a hard and glossy enamel-like appearance. The application of such material is time consuming and requires considerable care often calling for the skill of a professional manicurist. Furthermore the material once applied requires considerable time to dry and solidify during which period the digits must remain immovable to avoid smearing or other marring of the polished surface. As a further disadvantage, the polish material, being in direct contact with the hard nail surface, becomes easily chipped and readily peels off after short periods of use and as a consequence must be frequently reapplied, each 20 reapplication usually necessitating a thorough cleansing of the nail surface with a solvent or other polish removing material.

Attempts have been made in the past to avoid some of the foregoing difficulties and disadvantages connected with the use of liquid polish by providing the polish in preformed solid films conforming in shape to the nail. Such attempts have contributed little advance in the art in that the nail films are extremely brittle, will not permit the usual cutting or trimming of the nails after the films have been applied and also are so insecurely attached to the nail that they are readily dislodged during normal activity of the user.

It is an object of the present invention to cure all the foregoing and other disadvantages attendant upon the use of liquid nail polishing material and actually to contribute to the art important and valuable advantages where prior attempts have failed to do so.

More specifically, it is an object of the invention to provide nail polishing material of the conventional or any other suitable kind in a pre-formed solidified film but, instead of being adapted for direct application to the nail through the medium of an adhesive, the film forms a part of a compound laminated structure which is adapted to be applied to the surface of the nail. Devices constructed in accordance with the present invention require no skill to apply; present a natural appearance without any feeling of artificiality; the polished surface material is protected against chipping or peeling off; will not be damaged when the nail is cut and indeed are adapted to be cut or trimmed along with the nail, are extremely more durable in use than liquid polishing materials and prior substitutes therefor; provide protection for nails; improve the condition and stimulate growth of the nails;

and, since the polish material is not in direct contact with the nails, may be used by persons having allergy to many kinds of such material.

Other objects and advantages of the present invention will be apparent from the following detailed description taken in conjunction with the accompanying drawings wherein a preferred embodiment of the principles of the invention has been selected for exemplification:

In the drawings:

Fig. 1 is a representation of the human hand showing the manner in which devices constructed according to the invention are applied to the nails of the digits;

Fig. 2 is a longitudinal sectional view taken through one of the nail covering devices shown in Fig. 1;

Fig. 3 is a sectional view taken along the line 3—3 of Fig. 2;

Fig. 4 is a perspective view showing one form of packaging a set of the devices sufficient for application to all the nails of the hand or toe digits in a stack having the adhesive surface of one device in contact with the polished surface of another; and

Fig. 5 is a perspective view of a modified form of packaging a set of the devices mounted on a ribbon of cellophane or other suitable carrier sheet wound in a spool.

Referring more particularly to the drawings, wherein like numerals refer to like parts, the nail covering structure indicated in its entirety at A is a compound laminated body composed of a thin film of solidified nail polishing material 10 secured to sheet material, preferably in the form of fabric 12, the exposed face of which is provided with any suitable adhesive substance 14. In a convenient form of the invention, the parts 12 and 14 may be ordinary adhesive tape.

The sheet material 12 and, or, the adhesive substance 14 may be white or flesh colored or tinted a color similar to the color of the polish material 10. It is understood that the polish material 10 may be provided in a great variety of different colors and tints to suit the desires or occasions of the particular user.

In manufacturing the nail covering devices A, I prefer to support the sheet material 12, which may be in the form of strips, with the adhesive surface 14 in contact with a base of glass, porcelain, enamel or other suitable material to which the material 14 will not particularly adhere. Such a base may be flat or it may be slightly arcuate, conforming in general to the curvature of the human nail. The material 12 should be smoothed prior to application of the polish material. It is desirable to treat the surface of the sheet material 12 with a suitable material such as acetone in order to increase the tendency of the polish material 10 to adhere thereto. It is

important also that the material 12, if not already in this condition, be treated in such a manner that the surface thereof have a degree of porosity or, if of fabric, that the interstices between the woven thread remain open so that the polish material 10 when it is applied will find its way into such interstices or otherwise become imbedded within the body of the sheet 12 so as to provide a secure bond between the materials when the polish 10 solidifies.

The polish material 10 may be applied to the sheet 12 in any suitable manner such as by spraying, pouring or spreading with a brush or the like, it being desirable that the coating be of a uniform thickness sufficient to present a perfectly smooth outer surface. The polish material 10 is then dried in any well-known manner.

The thus laminated structure is then ready to be stamped or cut out by dies into approximate nail shapes and sizes such as indicated at A. Preferably the individual nail coverings A are made slightly larger than the nail to be covered thereby, it being intended in most instances that the ends of the devices be trimmed after application to the nail.

The layer of polish 10 is impervious to air and moisture and, firmly keyed to its pliant sheet material base 12, does not possess the usual brittleness or tendency to peel but instead assumes the pliant flexible characteristics of the material 12.

A preferred form of packaging the devices A for use is shown in Fig. 4 wherein sets of the devices, five or ten, in numbers sufficient to cover the nails of the digits of a hand or foot are stacked with the adhesive surface of one pressed firmly against the polish surface of the adjacent device. I have found that when packed in this manner the adhesive quality of the material 14 will actually be restored. Thus, after a set of the devices has been worn by the user and it is desired to change, say to another color, adhesive quality of the material 14 can be fully restored if the devices are assembled in the manner shown and as a consequence the devices are ready for reapplication whenever desired. Further, when initially prepared for the market in the form of a stack, the utmost compactness is provided and the devices may be stored over long periods of time without danger of deterioration.

Another convenient manner of presenting the devices A for the user is shown in Fig. 5 wherein the devices may be mounted in sets of any suitable number of rows upon a strip of any suitable material, cellophane for example, having a surface to which the material 14 is adherent but not sufficiently so to prevent ready removal of the devices when the same are to be put into use. Such strips may be compactly folded in any desired manner or, as shown, may be wound upon a support in spool form from which they may be unreeled as the devices are used.

In applying the devices A to the nails it is suggested that they be pressed so that the adhesive 14 is in firm contact with the underlying surface of the nail and the outer polished surfaces of the devices be rubbed with the fingers to remove any wrinkles. It is intended then that the devices, as well as the ends of the nails, if desired, be trimmed, preferably with the conventional curved manicuring scissors so that the ends of the devices are flush with the ends of the nails. It is suggested also, after the devices are thus applied, that the hands or feet be washed in

warm soapy water followed by running the thumb firmly over each nail to remove any bubbles and remaining wrinkles. Such washing also further removes any feeling of artificiality and the nails will then present a perfectly smooth and uniformly polished appearance. This most desirable condition will be maintained for many weeks and will not be impaired by bathing, washing or the performance of other vigorous household duties by the user. As the nails grow they may be trimmed or filed with an emery board without removing the covering devices.

It will be understood that the particular form and construction of the nail covering devices and the methods of manufacturing the same and of manicuring the nails herein shown and described are exemplary only of preferred embodiments of the invention which embraces within its concept such other forms or modifications as may come within the scope of the following claims.

I claim:

1. A decorative covering for the nail of a human digit formed of a pliable laminated structure having an outer layer of solidified nail polish material secured to an inner layer of sheet material and a layer of adhesive material carried by the exposed face of said inner layer, the said covering being of a size and curvature substantially conforming to the surface of said nail, the said inner layer of sheet material comprising a fabric.
2. The article of claim 1 wherein the layer of polish material projects into the interstices of the fabric layer and is keyed thereto.
3. A multi-layer sandwich comprising in juxtaposition: a sheet of flexible fabric, an ornamental film layer secured to one surface of the fabric sheet, and an adhesive layer secured to the other surface of the fabric sheet, the entire sandwich conforming generally in outline to the shape of a normal human digital nail.
